AUGUST VAGT, OF LEVERKUSEN, NEAR COLOGNE, GERMANY, ASSIGNOR TO FARBEN-FABRIKEN VORM. FRIEDR. BAYER & CO., OF ELBERFELD, GERMANY, A CORPORATION OF GERMANY.

PROCESS OF PRODUCING SULFONIC ACIDS.

1,102,827.

Specification of Letters Patent.

Patented July 7, 1914.

Application filed December 6, 1911. Serial No. 664,204.

To all whom it may concern:

Be it known that I, AUGUST VAGT, doctor of philosophy, chemist, citizen of the German Empire, residing at Leverkusen, near Cologne, Germany, have invented new and useful Improvements in Processes of Producing Sulfonic Acids, of which the following is a specification.

My invention relates to a new and valuable process of splitting off sulfonic groups from aromatic sulfonic acids which process consists in bringing the said organic compounds in contact with an amalgam of an alkali-forming metal, *e. g.*, alkaline or earth alkaline metal, that has been produced by electrolysis. The reaction is carried out in a separate chamber being in communication with the electrolyzer by a layer of mercury, the latter being kept in circulation. In the accompanying drawings which show one form of apparatus in which the present process can be carried out the chamber *a* has in its bottom a layer of mercury into which the cylinder *b* dips, the mercury thus forming a seal. The anode *c* is inserted in the liquid contained in the cylinder *b* and the other connection is obtained by means of the wire *d* which extends into the layer of mercury. A stirrer *f* is provided for the liquid *g* in the outer chamber.

In order to illustrate my invention the following example is given, the parts being by weight:—On the bottom of a chamber is a layer of mercury of about 1 to 2 centimeters depth. Into the mercury the cylinder *b* dips. In this cylinder caustic soda lye is decomposed by an electric current which is introduced by the anode *c* and the isolated thread *d*. The stirrer *f* keeps in motion the mercury which absorbs the sodium in *b* and carries the amalgam into *g* where the reduction takes place. 250 parts of 1-naphthylamin-3.8-disulfonic acid (di-sodium salt) are dissolved in 2000 parts of water and poured into the chamber *a*. The caustic soda lye in the chamber *b* is a 25 per cent. lye.

The electrolysis is carried out with an electric current of 10-20 amperes on 50 square centimeters while it is stirred. When in *g* the quantity of sodium sulfite produced by the sulfonic group being split off shows that one group is split off, the solution is

acidulated, boiled and the 1-naphthylamin-3-sulfonic acid is filtered off. In the same way the following acids can be produced: From anilin-3.6-disulfonic acid the anilin-3-monosulfonic acid, from 1-naphthylamin-4.8-disulfonic acid the 1-naphthylamin-4-sulfonic acid, from 2-naphthylamin-4.8-disulfonic acid the 2-naphthylamin-8-sulfonic acid, from 2-naphthylamin-5.7-disulfonic acid the 2-naphthylamin-7-sulfonic acid, from 1-naphthylamin-3.5.7-trisulfonic acid the 1-naphthylamin-3.7-disulfonic acid, from 1-naphthylamin-2.4.6-trisulfonic acid the 1-naphthylamin-2.6-disulfonic acid, from 1-naphthylamin-2.5.7-trisulfonic acid the 1-naphthylamin-2.7-disulfonic acid, from 1-naphthol-3.8-disulfonic acid the 1-naphthol-3-sulfonic acid, from 1-naphthol-2.4.8-trisulfonic acid the 1-naphthol-2.4-disulfonic acid and from 2-naphthol-3.6.8-trisulfonic acid the 2-naphthol-3.6-disulfonic acid.

I claim:—

1. The process of splitting off sulfonic groups from aromatic sulfonic acids which comprises continuously producing an amalgam of an alkali-forming metal and circulating such freshly prepared amalgam into contact with the aromatic sulfonic acids.

2. The process of splitting off sulfonic groups from aromatic sulfonic acids which comprises continuously producing sodium amalgam and circulating such freshly prepared amalgam into contact with the aromatic sulfonic acids.

3. The process of splitting off sulfonic groups from aromatic sulfonic acids which comprises producing an amalgam of an alkali-forming metal electrolytically, circulating such electrolytically prepared amalgam in contact with the aromatic sulfonic acids, and continuing the electrolytic production of the amalgam and the reduction of the sulfonic acids by circulating the same amalgam alternately into reactive relation with the electrolytic bath and with the acid.

4. The process of producing aromatic sulfonic acids from aromatic poly-sulfonic acids containing a larger number of sulfonic acid groups which comprises circulating in contact with such acids electrolytically prepared amalgam of an alkali-forming metal in which amalgam the alkali-

100

105

forming metal is replaced continuously as the re-action progresses.

5. The process of splitting off sulfonic groups from aromatic poly-sulfonic acids and of producing aromatic sulfonic acids containing a smaller number of sulfonic acid groups which comprises producing an amalgam of an alkali-forming metal electrolytically and circulating such freshly prepared amalgam into contact with the aromatic poly-sulfonic acid continuously, the alkali-forming metal of the amalgam being replaced continuously in the amalgam and the strength of the amalgam being thereby maintained approximately constant.

6. The process of splitting off sulfonic groups from aromatic poly-sulfonic acids

and of producing aromatic sulfonic acids containing a smaller number of sulfonic groups which comprises producing sodium amalgam electrolytically and circulating such freshly prepared amalgam into contact with the aromatic poly-sulfonic acid continuously, the sodium of the amalgam being replaced continuously in the amalgam and the strength of the amalgam being thereby maintained approximately constant.

In testimony whereof I have hereunto set my hand in the presence of two subscribing witnesses.

AUGUST VAGT. [L. s.]
